(57) **CLAIM**

The ornamental design for a cell phone holder, as shown and described.

DESCRIPTION

FIG. 1 is a front perspective view of the cell phone holder showing the present design.

FIG. 2 is a left view thereof.

FIG. 3 is a front view thereof.

FIG. 4 is right side view thereof.

FIG. 5 is a top view thereof.

FIG. 6 is a rear view thereof; and,

FIG. 7 is a bottom view thereof.

The circular features of the front surface as shown in FIGS. 1 and 2 are not individually shaded to more clearly show the surface configuration. The oblique shading on the front surface indicates that the entire surface is transparent.
